UNITED STATES PATENT OFFICE

160,849

HANDLE FOR COFFEE MAKERS

Hoyt Keith Foster, Hollis, N. Y., assignor to S. W. Farber Inc., New York, N. Y., a corporation of New York

Application March 1, 1950, Serial No. 8,228

Term of patent 14 years

(Cl. D44—29)

To all whom it may concern:

Be it known, that I, Hoyt K. Foster, a citizen of the United States, residing at Hollis, county of Queens, State of New York, have invented a new, original, and ornamental Design for a Handle for Coffee Makers, of which the following is a specification, reference being had to the accompanying drawing, forming a part thereof.

I claim:

The ornamental design for a handle for coffee makers, as shown.

HOYT KEITH FOSTER.
